UNITED STATES PATENT OFFICE.

JOHN J. MCINTYRE AND CHARLES KOEHLER, OF HARTFORD, CONNECTICUT.

BALL-LAPPING MACHINE.

1,330,083.

Specification of Letters Patent.

Patented Feb. 10, 1920.

Application filed April 7, 1919. Serial No. 288,409.

To all whom it may concern:

Be it known that we, JOHN J. MCINTYRE and CHARLES KOEHLER, citizens of the United States, residing at Hartford, in the 5 county of Hartford and State of Connecticut, have invented a new and useful Improvement in Ball-Lapping Machines, of which the following is a specification.

This invention relates to those machines 10 which are provided for finishing balls for bearings, and the like purposes, to final shape and size, which machines are commonly termed "ball lapping machines," although the invention is also applicable to 15 grinding machines which reduce such balls to approximately final size.

These machines generally have two plates arranged face to face with their opposing faces provided with equal numbers of complementarily arranged concentric grooves, 20 one plate being fixedly mounted and the other rotarily mounted. The fixed plate is commonly made of cast iron and the rotary plate of cast iron if for lapping balls, or of 25 abrasive material if for grinding balls. The balls are usually fed to the innermost groove between the opposing faces of the plates and they are passed around and transferred from one groove to the other so that 30 each ball travels the same path as, and is subject to the same action as every other ball, in order that all of the balls shall receive identically the same treatment and be reduced to exactly the same size.

35 The object of this invention is to simplify the construction and reduce the cost of manufacture of such machines, and increase their accuracy, thereby cheapening the output and insuring uniformity of the product.

40 This object is attained by arranging for the entrance of the balls through the fixed plate to the innermost groove and providing for the transfer of balls from groove to groove outward by means of the rotating 45 plate, in such manner that the balls will travel around all of the grooves without liability of wedging and clogging the machine, thereby insuring a continuous outflow of balls of exactly the same size.

50 Figure 1. of the accompanying drawings shows a diametrical section taken through two lapping plates of a machine constructed according to this invention. Fig. 2 shows a face view of the fixed plate. Fig. 3 shows a face view of the rotary plate. Fig. 4 shows an edge view of a portion of the

fixed plate and the ball entrance feed. Fig. 5 on a larger scale shows sections of portions of the fixed and rotary plates illustrating the manner of transferring the balls 60 from one groove to the other. Fig. 6 shows a section through a ball transfer pocket of the rotary plate, on the line 6-6 on Fig. 3.

The fixed plate 1 is usually made of cast iron in the form of an annular disk with a 65 number of concentric grooves 2, the cross section of each of which grooves is nearly semi-circular. This grooved plate, which, of course, can be made of other material if desired, is attached to a backing plate 3 70 which is fixed in the machine in the usual way. The grooved plate has a feed tube 4 that enters downwardly at the back and communicates with the in-most groove. At the top the edge of this plate is cut away 75 so as to open the outside groove to permit the discharge of balls which have traveled around through all of the grooves and are reduced to the required size.

The plate 5 of cast iron or abrading material—according to the use to which the machine is to be put—is made in the form of an annular disk and has similar concentric grooves 6. The grooves, when the two active plates are arranged face to face, complement each other and form the passageways for the balls. This plate 5 is attached to a backing plate 7 that is mounted in the machine on an arbor so that it may be rotated at the required speed. In the grooved 80 face of the rotary plate, opposite the end of the inside groove and extending across to the next outer groove, is a pocket 8. Extending from the second groove to the third groove at another locality is a pocket 9, and 85 arranged at various places so as to permit communication from an inner to the next outer groove are similar pockets 10. The walls of these pockets are arranged so that they incline from the inner wall of the inner groove to the inner wall of the next outer groove, as illustrated in the views.

When the plates are arranged face to face and the rotary plate is set in motion, balls which are fed through the fixed plate into 105 the inside groove are rolled around by the movement of the rotary plate, and as, of course, they advance along the groove at only one-half the speed of travel of the rotary plate they are ground or reduced in 110 diameter. The balls when they reach the pockets in the rotary plate at the ends of the

grooves are thrown off and by the walls of the grooves and centrifugal force are directed into the next outer grooves. As a result of this all of the balls travel through all 5 of the grooves, that is, every ball takes the same path as every other ball and is subject to the same action. Consequently, the grooves wear evenly and the balls are reduced uniformly so that they come out at 10 the space at the end of the outermost groove all exactly the same size. It is a simple matter to form these pockets in the rotary plate for transferring the balls from one groove to another, and under centrifugal action the 15 balls are surely thrown out by the rotary plate into the next outer groove without liability of clogging and interfering with the action of or damaging the plates.

The invention claimed is:—

- 20 1. In a ball sizing machine the combination of a fixed plate with a series of concentric grooves, and a rotary plate with a series of concentric grooves that at one locality in each groove are closed by a wall, the plates 25 said plates being arranged with their grooved faces opposing each other, and said

rotary plate having pockets in front of said closing walls for transferring balls from each inner to each outer groove.

2. In a ball sizing machine the combination of a fixed plate with a series of concentric grooves, a rotary plate with a series of concentric grooves that at one locality in each groove are closed by a wall, the plates being arranged with their grooved faces 30 opposing each other, said fixed plate having an opening for feeding balls to one groove, and said rotary plate having pockets with outwardly inclining walls adjacent to said closing walls for transferring balls from 35 each inner to each outer groove.

3. In a ball sizing machine the combination of a fixed plate having a series of concentric grooves and a ball feed opening, and a rotary plate having a series of concentric 40 grooves and pockets of a width of two grooves formed at different localities, said pockets having inclined walls closing each inner groove and leading from each inner to each outer groove.
